UNITED STATES PATENT OFFICE.

WILMOT STEPHENS, OF BINGHAMTON, NEW YORK.

INDICATOR.

SPECIFICATION forming part of Letters Patent No. 253,819, dated February 7, 1882.

Application filed November 22, 1881. (Model.)

To all whom it may concern:

Be it known that I, WILMOT STEPHENS, a citizen of the United States, residing at Binghamton, in the county of Broome and State 5 of New York, have invented certain new and useful Improvements in Indicators; and I do hereby declare the following to be a full, clear, and exact description of the invention, such as will enable others skilled in the art to which 10 it appertains to make and use the same.

The object of my invention is the construction of a business-indicator and card-holder of very simple form, consisting of three parts only, for use in offices or houses.

15 My improvement is illustrated in the accompanying drawings, in which Figure 1 is a front view of the same; Fig. 2, a side sectional view, and Fig. 3 a rear view, in elevation, of the front plate and disk connected therewith.

20 My invention consists of the following principal parts, viz: a front plate, A, a rear plate, B, and a center disk, C, provided with a thumb-piece, D, and constructed and arranged in the manner and for the purpose hereinafter described.

I prefer to make the front and back plates 25 of cast-iron, in the form shown; but they may be made of other material and in other forms. The thin center disk may be of tin, card-board, 30 or other suitable material. The front plate is provided with a slot, C, through which can be seen the margin of the center disk, on which is inscribed or printed any desired announcements in words or figures. The center disk. 35 rests in an annular recess, e, formed in the back of the front plate, and is attached to the shank of the thumb-piece D, which extends through the front plate, and by which thumb-piece the said disk is turned to present the de-

sired announcement at the slot. A flange, g, 40 is formed on the back of said front plate around the recess e, projects a slight but uniform distance beyond the disk, and its upper surface is flat. The object of this formation of the flange is to present a flat surface to the back 45 plate when the two plates are bolted together, and at the same time form a slight recess and support, h, at the upper portion of the indicator, over the disk, for the reception of cards. To facilitate the holding of the cards the back 50 plate extends above the front plate, as shown in the drawings. The two plates are provided with holes at corresponding places, as shown at f, through which screws or nails may be passed to hold the plates together and fasten 55 the same to a door or other surface.

Having thus described my invention, what I claim, and desire to secure by Letters Patent, is—

1. In a business-indicator and card-holder, 60 the combination of the front plate provided with an annular recess, e, and a flange, g, the center disk fitting into said recess, and the back plate fitting closely against said flange, substantially as described. 65

2. In a business-indicator and card-holder, the combination of the two plates A, B, the front one provided on its back with a circular flange and the back one fitting flatly against 70 said flange and extending above the front plate to form the card-holder, substantially as described.

In testimony whereof I affix my signature in presence of two witnesses.

WILMOT STEPHENS.
